UNITED STATES PATENT OFFICE.

JOHN W. FITCH, OF RACINE, WISCONSIN, ASSIGNOR TO RACINE ENGINE & MACHINERY CO., OF RACINE, WISCONSIN, A CORPORATION OF WISCONSIN.

SHAKING DISCHARGE MECHANISM.

1,324,735.

Specification of Letters Patent.

Patented Dec. 9, 1919.

Application filed January 16, 1915. Serial No. 2,620.

To all whom it may concern:

Be it known that I, JOHN W. FITCH, a citizen of the United States, residing at Racine, in the county of Racine and State of Wisconsin, have invented certain new and useful Improvements in Shaking Discharge Mechanism, of which the following is a description.

My invention relates to mechanism for discharging the product of machines for cutting or forming candy or similar substance adapted to thoroughly separate the product into its several parts or pieces.

The object of my invention is to produce a simple, convenient and reliable device of the kind described in which the movements of the discharging mechanism may be regulated to suit the material or product being discharged and to avoid unnecessary bruising or disfiguring of the pieces passing through the device.

To this end my invention consists in the novel construction, arrangement and combination of parts herein shown and described and more particularly pointed out in the claims.

In the accompanying drawings wherein like or similar reference characters indicate like or corresponding parts:

30. Figure 1 is a side elevation of my device. Fig. 2 is an end elevation of the same.

Fig. 3 is an enlarged fragmentary elevation of the discharge spout and associated parts on my device with parts removed and broken away to more clearly show the construction.

Fig. 4 is a partial section taken substantially on line 4—4 of Fig. 3.

In the form shown in the drawings a suitable frame comprising a pair of pillars 1—1 is provided near the upper end of which a roller or sheave 2 is mounted adapted to operate as the end roller for a carrier belt 3 for conveying the formed material to my device.

As shown a shaft 4 is mounted in suitable bearings on the frame 1 or adjacent portions of the mechanism and provided with a gear wheel 5 adapted to mesh with and drive a gear wheel 6 rigidly attached to the supporting shaft of the sheave 2 for operating the conveyer belt 3. In the form shown also an air pipe 7 is provided above the conveyer belt for discharging cool air upon the material upon the belt to chill the same and thus

rendering the pieces more brittle and preventing their sticking together when discharged from my device.

My improved mechanism consists of suitable apparatus arranged to receive the material from the belt 3 and discharge the same into a suitable receptacle at the same time operating to break and separate the several parts passing through my device and freeing them from the associated material.

In the form shown a shaft 8 is mounted in suitable bearings 9—9 on the respective portions of the frame 1 and an eccentric portion 10 is rigidly attached to, or formed integrally upon, the shaft 8 between the bearings 9. A trough 11 of any suitable form or construction is provided to receive the material from the belt 3 and direct the same into the desired receptacles.

Any suitable means may be provided upon the trough 11 to engage the eccentric portion 10 of the shaft 8 to shake the trough. As shown a bearing 12 is fitted to the eccentric portion 10 and provided with a face adapted to engage and fit against the bottom of the trough 11 with suitable arms 14 or other convenient means extending on each side of the trough each provided with suitable means adapted to rigidly secure the arm to the side of the trough. As shown the side walls of the trough 11 are each provided with suitable slots 16 extending longitudinally of the trough substantially parallel with its bottom to provide a suitable support for the trough and for the convenient adjustment of the bearing longitudinally of the trough.

Suitable means are also provided to engage one end of the trough to hold the same in a suitable position. In the form shown a link 17 is pivotally mounted between the pillars 1—1 as at 18 and attached to the trough 11 as at 19 thus permitting the free movement of the free end of the trough both longitudinally and vertically when the shaft 8 is rotated. In the preferred form also a part 20 is provided upon the link 17 beyond the bearing 18 to counterbalance the weight of the trough to avoid vibration in the frame and secure the smooth operation of the device. In the preferred construction a vertical slot 21 is provided in each of the pillars 1 and each end of the bearing 18 of the link 17 extends into the slots with a suitable nut 22 or other convenient means at the outer

end of the bearing adapted to rigidly clamp the bearing in position on the frame to control the inclination.

In the preferred construction suitable means are provided for directing material into the trough. As shown a chute 24 extending from a point near the periphery of the sheave 2 to the bottom of the trough is provided and rigidly attached to the frame 1 by brackets 25 or other convenient means rigidly attached to the frame and chute. A guard 26 also extends across the trough and is rigidly secured to the walls thereof in position to engage and direct material from the belt 3 into the trough and prevent the movements of the trough from unnecessarily throwing material passing therethrough.

Suitable means are also provided for rotating the shaft 8 to shake the trough. In the form shown a gear wheel 27 is mounted upon the shaft 8 coöperating with a gear wheel 28 rotatably mounted upon the frame 1 and rigidly connected to a pinion 29 which in turn meshes with a gear 30 rigidly connected to the sheave 2. The several parts are so constructed and arranged that any rotation of the sheave 2 will produce a rapid rotation of the shaft 8 thereby rapidly oscillating the free end of the trough 11 the movements of the trough however may be controlled within certain limits by adjusting the position of the bearing 12 longitudinally thereof. When the bolt 15 is positioned at the end of the slot 16 adjacent the free end 35 of the trough thus bringing the bearing 12 to the limit of its movement toward the free end of the trough, the movements of the trough are comparatively slight. As the bearing is moved toward the opposite end of the trough however it is obvious that the movement of the free end of the trough will increase rapidly owing to the relative positions of the bearing 12 and the fulcrum of the trough formed by its connection to the link 17.

Having thus described my improvement, it is obvious that various immaterial modifications may be made in my device without departing from the spirit of my invention hence I do not wish to be understood as limiting myself to the exact form or construction.

What I claim as new and desire to secure by Letters Patent is:

1. In a device of the kind described, a frame, a shaft having an eccentric portion rotatably mounted upon said frame, a trough mounted upon the eccentric portion of said shaft and means for adjusting the position of said trough upon said shaft, in combination with a link connecting one end of said trough to said frame, means for rotating said shaft and means for directing material into said trough.

2. In a device of the kind described, a frame, a shaft having an eccentric portion rotatably mounted upon said frame, a trough mounted upon the eccentric portion of said shaft and means for adjusting the position of said trough upon said shaft longitudinally of the trough, in combination with a link connecting one end of said trough to said frame, means for rotating said shaft and means for directing material into said trough.

3. In a device of the kind described, a frame, a shaft having an eccentric portion rotatably mounted upon said frame and a trough mounted upon the eccentric portion of said shaft, in combination with a link connecting one end of said trough to said frame, means for adjusting the connection between said link and frame, means for rotating said shaft and means for directing material into said trough.

4. In a device of the kind described, a frame, a shaft having an eccentric portion rotatably mounted upon said frame, a trough, a bearing rigidly attached to said trough and extending transversely thereof intermediate its ends and mounted upon the eccentric portion of said shaft and means for adjusting the position of said bearing upon said trough, in combination with a link connecting one end of said trough to said frame, means for rotating said shaft and means for directing material into said trough.

5. In a device of the kind described, a frame, a shaft having an eccentric portion rotatably mounted upon said frame, a trough attached intermediate its ends to the eccentric portion of said shaft and means for adjusting the position of said trough upon said shaft, in combination with a counterbalanced link connecting one end of said trough to said frame, means for adjusting the connection between said link and frame, means for rotating said shaft and means for directing material into said trough.

6. In a device of the kind described, a frame, a shaft having an eccentric portion rotatably mounted upon said frame and a trough mounted upon the eccentric portion of said shaft, in combination with a counterbalanced link connecting one end of said trough to said frame, means for adjusting the connection between said link and frame, means for rotating said shaft and means mounted upon said trough for directing material into said trough.

In testimony whereof, I have hereunto signed my name in the presence of two subscribing witnesses.

JOHN W. FITCH.
